Inventor:
Georgia A. Post
by James R. Hodder
Atty.

UNITED STATES PATENT OFFICE.

GEORGIA A. POST, OF WEST LONG BEACH, NEW YORK.

TOY SAFETY-RAZOR OUTFIT.

Application filed September 29, 1924. Serial No. 740,567.

To all whom it may concern:

Be it known that I, GEORGIA A. Post, a citizen of the United States, and resident of West Long Beach, in the county of Nassau 5 and State of New York, have invented an Improvement in Toy Safety-Razor Outfits, of which the following description, in connection with the accompanying drawings, is a specification, like reference characters 10 on the drawings representing like parts.

My present invention relates to a toy safety razor and more particularly to such a toy safety razor in combination with a brush enclosed therein, and a novel shaving 15 soap.

So far as I am aware there has never been devised a toy shaving outfit particularly for young boys. It is a well known fact that when a boy reaches a certain age, he is 20 obsessed with a desire to emulate older men. Particularly is this noticed in the desire of many young boys to imitate their fathers or older brothers in shaving. The result of this is that they frequently endeavor to 25 carry out such imitations with the older person's own razor, frequently resulting in serious cuts and other injuries.

An important object of my present invention, therefore, is to provide a toy safety 30 razor which will be absolutely fool-proof, and with which the child will be unable to injure himself.

A further feature of my present invention is to provide a shaving brush, concealed 35 within the handle of the razor, and operable by very simple means.

A further important object of my present invention is to provide with the aforesaid 40 razor and brush a "whisker shaving soap". This soap may be either a powder, cream, cake, or stick, and has fixed therewith small particles of finely chopped bristles. Thus, when the boy lathers his face with the whisker shaving soap, he has worked up a 45 lather having therein these particles of bristles simulating the natural hair of the face. The result is that when he removes this lather from his face with the toy safety razor, he has the sensation of actually shaving, superinduced by the sight of the 50 bristles in the lather, and it may well be that the child's imagination will render this a very pleasing amusement.

Further features of the invention, novel 55 combinations of parts and advantages will

be hereinafter more fully pointed out and claimed.

Referring to the drawings, illustrating preferred embodiments of my invention.

Fig. 1 is a side view of my novel razor 30 in closed form, illustrating the brush contained within the handle;

Fig. 2 is a front view of the same;

Fig. 3 is a side view of the razor with the brush extended in operating position; 65

Fig. 4 is a side view of the razor with no brush therein;

Fig. 5 being a side view partly broken away, illustrating the brush receiving recess and the stop for a cover; 70

Fig. 6 illustrating the brush; and

Fig. 7 illustrating generally my novel whisker shaving soap.

Referring to the drawings, my novel toy razor comprises a hollow handle 1, having 75 integrally secured thereto an imitation blade and guard portion 2. This shaving portion 2 is curved and shaped to simulate the ordinary shaving head of a safety razor, but not being provided with any blade, there 80 is no possibility of the child injuring himself by using the same. On the lower portion of the handle 1, I provide a cap or cover 3, this cap or cover fitting over the end of the handle 1, and abutting against 85 the peripheral flange 4. The cap 3 is maintained in position on the handle 1 by the snugness of its fit thereover. In the handle 1 is also provided a slot 5, this slot having at either end thereof bayonet joint sockets 90 6 and 7. The brush for use in combination with my novel toy razor comprises the bristles 10, a ferrule or band 11, and a projecting knob 12. This brush is adapted to fit within the hollow handle 5, and when in 95 closed position, the knob 12 fits within the bayonet joint socket 6, so that the brush bristles are entirely concealed within the handle 1, whereupon the cap 3 is fitted over the lower end of the handle, and the same 100 then is in compact form as illustrated in Figs. 1 and 2. When it is desired to utilize the brush for working up a lather, the cap 3 is removed, the knob 12 moved sideways out of the socket 6, slid downwardly along 105 the slot 5, and then sideways until the knob 12 engages with the bayonet joint socket 7. The brush is now in the position as illustrated in Fig. 3, ready for use.

I may desire to utilize a toy safety razor 110

separate and apart from the brush element, and have illustrated in Fig. 4 such a razor, comprising a handle 20, an imitation shaving portion 21, and an enlarged end portion 22 for facility in holding. With this form of

the size, shape and arrangement of parts within reasonably wide limits without departing from the principle of the invention. 30

My invention is further described and defined in the form of claims as follows:

1. A toy safety razor outfit, comprising an imitation razor, a brush contained in the handle thereof, and a soap for use therewith, said soap having mixed therewith particles of bristle. 35

2. A toy safety razor of the kind described, comprising a hollow handle, a slot in said handle, said slot having bayonet joint recesses at either end thereof, a brush member adapted to fit within the handle, and means on said brush adapted to be operated along said slot, said means cooperating with the bayonet joint recesses to hold said brush in operative and inoperative position, a cover adapted to fit over the open end of the handle, and a peripheral flange on said handle against which said cover abuts, and an imitation blade and guard portion on the opposite end of said handle. 40 45 50

In testimony whereof, I have signed my name to this specification.

GEORGIA A. POST.
